UNITED STATES PATENT OFFICE

MARCEL A. BRISINGER, OF KEARNY, NEW JERSEY

BUILDING CONSTRUCTION

Application filed May 6, 1930. Serial No. 450,087.

The invention relates to building construction and more particularly to the construction of interior walls of dwelling houses or any other buildings.

5 The principal object of the invention is the provision of a system of construction by which a satisfactory smooth, rigid and permanent surface may be formed upon the usual wooden studding or upon metallic supports without using the ordinary wooden or metallic lath and the conventional rough coat and finishing coat of plaster.

A further object is to provide a wall surface which is elastic and tough but not brittle, thereby eliminating the possibility of the development of cracks, either during the drying of the surface coating or under the influence of subsequent distortion of the wall surface.

20 A still further object is the construction of a wall which will absorb both sound and moisture thereby providing a wall which has both acoustic properties and long life under all climatic conditions.

25 Another object is the provision of a wall which will be healthier, more sanitary, warmer and more permanent than known types of walls.

In addition to the foregoing objects and 30 advantages a wall is provided which is less expensive in construction.

The invention contemplates the use of wall boards formed of a fibrous composition, numerous types of which are in the market; 35 completely covering the wall boards with sheets of fabric and applying a thin coat of plastic material to the fabric to provide a finishing surface. It is well known in the art to apply a finishing coat of plaster direct to such wall boards. However, the ordinary 40 finishing coat does not readily adhere to the wall boards and when it is applied in such fashion cracks almost invariably form at each of the meeting or abutting edges, rendering the wall unsightly and unsatisfactory for high grade work. It has been further proposed to cover the vertical and horizontal joints between the wall boards with strips of wire fabric. While this helps conditions to 45 some extent it still does not provide a satis-

factory wall. With this construction the finishing coat must be prepared with great care in order to adhere to the wall boards and a reasonably thick layer of plaster must be applied to the surface. With such a thick 55 layer, regardless of its constituency, cracks are bound to develop.

In accordance with the present invention the finishing coat is made of an elastic and tough but not brittle material and is applied 60 to the fabric in an extremely thin layer. A bond is thus actually formed between the finishing coat and the fabric and cracks are eliminated regardless of the ordinary distortion of the walls caused by settling of the 65 building, vibration or other causes.

Further objects and advantages of the invention will be in part set forth in the following specification and in part will be obvious therefrom without being specifically pointed 70 out, the same being realized and attained by means of the instrumentalities and combinations pointed out in the claims hereof.

For a complete understanding of the invention drawings have been provided in 75 which a preferred embodiment of the invention is illustrated. Referring to said drawings:

Fig. 1 is a fragmentary elevational view of 80 a wall constructed in accordance with the invention and having various layers broken away for clearness of illustration;

Fig. 2 is a sectional plan view taken on line 2—2 of Fig. 1, and in addition showing 85 the construction at a corner; and

Fig. 3 is a fragmentary detail sectional view on an enlarged scale and is taken on line 3—3 of Fig. 1, although said view might be a typical section through any part of the wall construction.

Referring again to said drawings the reference numeral 5 designates the main wall structure or studding. This studding may be of the conventional wooden structure, metallic supports or any approved construction. 95 In some cases, particularly in repair jobs, it may even be desirable to install the wall over the existing wall of wooden or metal lath, plaster board or whatever it might be.

Secured to the studding 5, preferably by 100

nails 6, are sheets of wall board 7. These sheets as illustrated extend from the floor line 8 to the ceiling (not shown). However, they may extend lengthwise of the wall if desired or may even be made up in small sections although the latter construction is not considered to be so advantageous. The wall boards are preferably formed of a fibrous composition such as cane, wood pulp, asbestos or similar substances. However, almost any of the numerous well known wall boards on the market are readily adaptable for the purpose. As illustrated the sheets of wall board are laid in abutting relation to each other. In Fig. 1 the width of the sheets of wall board are designated by the dimension lines marked *a*.

Sheets of fabric 9 are adhesively secured to the wall boards 7. The sheets of fabric are preferably formed of a tough muslin suitably treated although other fabrics may be used and even a wire mesh would not be precluded although a tough cloth fabric is preferred. The sheets of fabric completely cover the wall boards and as previously stated are firmly secured thereto by a suitable adhesive. In practice they would be applied to the wall boards in a manner substantially the same as wall paper is applied to a wall. The edges of the sheets of fabric are preferably laid in abutting relation, although this is by no means essential, and it is desirable that the abutting edges of the sheets of fabric be staggered in relation to the abutting edges of the wall boards. In this manner each of the joints between the wall boards will be covered by the fabric. Due to the elasticity or inherent stretch in the fabric it will be apparent that any natural weaving or distortion of the walls will not materially effect the fabric. It is preferable to lay the sheets of fabric in the same general direction as the sheets of wall board but this is not essential for instance, the sheets of fabric might be laid at right angles or diagonally to the sheets of wall board. In Fig. 1 the width of the sheets of fabric is designated by the dimension lines *b*. As illustrated the widths of the sheets of fabric are different from the widths of the wall board sheets. However, this may vary according to the standard widths of fabric and wall board used.

A thin coating of plastic material 10 is applied to the sheets of fabric 8. This plastic material is formed of any suitable substance which is tough and elastic but not too brittle. The fabric being more or less porous will absorb a certain amount of the coating of plastic material and a firm bond will be formed between the fabric and coating. Thus the coating of plastic material may be extremely thin. This makes for great economy of construction but principally provides a finishing surface which is hard, smooth, of

excellent appearance and will not crack. This is due to the extremely thin coating of plastic material and the fact that it may practically move with the fabric. While numerous types of plastic materials having the desired qualities may be employed, in practice it has been ascertained that a mixture of flat paint with substantially equal parts of plaster of Paris and whiting to bring it to the proper consistency forms a first class material. This also has the great advantage in that a flat paint of the desired color or tint may be selected and the expense of painting the wall is eliminated. However, a plastic material of a neutral color may be employed and a permanent hard finished surface is provided which may be painted or decorated in any desired manner.

At the corners of the room or between the walls and ceiling it is preferable to use a sheet metal angle 11 as shown in Fig. 2.

Changes in material, details of construction, and arrangements of parts may be made by one skilled in the art without departing from the spirit of the invention or the scope of the appended claims.

I claim:

1. An interior wall construction comprising, in combination with the main wall structure or studding, wall boards secured to said structure, sheets of fabric completely covering and secured directly upon the proximate face of the said wall boards, and a thin coating of plastic material laid on said sheets of fabric.

2. An interior wall construction comprising, in combination with the main wall structure or studding, fibrous composition wall boards secured to said structure, sheets of tough cloth fabric completely covering and adhesively secured directly upon the proximate face of the said wall boards, and a thin coating of plastic material laid on and forming a bond with said sheets of fabric.

3. An interior wall construction comprising, in combination with the main wall structure or studding, sheets of wall board secured in abutting relation to said structure, sheets of fabric completely covering and adhesively secured directly upon the proximate face of the said sheets of wall board, the joints between said sheets of wall board and said sheets of fabric being staggered in relation to each other, and a thin coating of plastic material laid on and forming a bond with said sheets of fabric.

4. An interior wall construction comprising, in combination with the main wall structure or studding, sheets of fibrous composition wall board nailed in abutting relation to said structure, sheets of tough cloth fabric completely covering and adhesively secured in substantially abutting relation directly to said sheets of wall board, the joints between said sheets of wall board and said sheets of

fabric being staggered in relation to each other, and a thin coating of plastic material laid on and forming a bond with said sheets of fabric.

5. An interior wall construction comprising, in combination with the main wall structure or studding, wall boards secured to said structure, sheets of fabric completely covering and adhesively secured directly upon the proximate face of the said wall boards, and a thin coating of plastic material laid on and forming a bond with said sheets of fabric, said plastic material comprising paint mixed with substantially equal parts of plaster of Paris and whiting.

In testimony whereof I affix my signature.
MARCEL A. BRISINGER.
